UNITED STATES PATENT OFFICE.

GEORGE LEWIS HOTCHKISS, OF PLAINVILLE, CONNECTICUT.

GAME.

SPECIFICATION forming part of Letters Patent No. 690,057, dated December 31, 1901.

Application filed October 23, 1901. Serial No. 79,736. (No model.)

To all whom it may concern:

Be it known that I, GEORGE LEWIS HOTCHKISS, a citizen of the United States, residing at Plainville, in the county of Hartford and 5 State of Connecticut, have invented a new and useful Game, of which the following is a specification.

The invention relates to improvements in games.

10 The object of the present invention is to provide a simple and comparatively inexpensive game which will possess the characteristics of base-ball and billiards and pool and which will be adapted to afford amusement 15 for a number of players.

The invention consists in the construction and novel combination and arrangement of parts hereinafter fully described, illustrated in the accompanying drawings, and pointed 20 out in the claims hereto appended.

In the drawings, Figure 1 is a perspective view of a game-board constructed in accordance with this invention. Fig. 2 is a sectional view of the same.

25 Like numerals of reference designate corresponding parts in all the figures of the drawings.

1 Designates a rectangular game-board designed to be constructed of wood or any other 30 suitable material and adapted to be made of various sizes, and it may, if desired, form the top of a table and be provided with supporting-legs. The rectangular board is provided at its edges with a marginal flange 2 to prevent balls 3 and 4 from leaving it, and it has an inclined way 5, consisting of a channel or 35 groove gradually increasing in depth and arranged parallel with the side edges of the game-board, as clearly illustrated in Fig. 1 40 of the accompanying drawings. At the sides of the board are arranged cushions 6, consisting, preferably, of wires stretched between pins 7 and spaced apart at the corners of the board to form openings or ways, and the said 45 corners of the board represent the home base, the first base, the second base, and the third base. The pins 7 are embedded in the board at the sides of the field, and the wires are suitably secured to them; but any other form of 50 cushion may be employed for causing the balls to rebound and for preventing them from en-

tering the inclined way except as hereinafter explained.

At the center of the field is arranged a small diamond or rectangle 8, which may be marked 55 off in any suitable manner, or a rectangular space of a color different from the rest of the field may be provided for designating the place for spotting the cue-ball 3 at the commencement of an inning. A similar but 60 slightly smaller diamond or rectangular space 9 is arranged at the home corner and at the entrance of the inclined way for designating the place or point at which the object-ball is 65 spotted.

The corner space or entrance 10 between the cushions 6 at the left-hand side of the field is the first base, and the space or entrance 11 opposite the home corner is the second base, and the space or entrance 12 at the 70 right-hand side of the field is the third base. After the balls have been spotted the player leading off takes the position at the second base and with a cue (not shown) drives the cue-ball 3 in the direction of the object-ball 75 and endeavors to cause the object-ball 4 to roll into the inclined way 5, which surrounds the field. If he succeeds in accomplishing this result, the object-ball will roll slowly around the field to the home corner, and if 80 uninterrupted, as hereinafter explained, will constitute one run.

Within the home corner is arranged an approximately U-shaped cushion 13, having an extended side 14 and provided with a curved 85 back portion adapted to cause the cue-ball to return to the field—say to the position illustrated in dotted lines in Fig. 1 of the accompanying drawings. Then the player who is opposed to the first player endeavors to roll the 90 cue-ball through one of the open spaces or entrances at the corners of the field into the inclined way at a point directly in advance of the object-ball. If the second player succeeds in this attempt either at the first, sec- 95 ond, or third base corners, the run does not count and the object-ball is “put out.” The first player in attempting to roll the object-ball into the inclined way has three trials, which correspond to the strikes of a player 100 in a game of base-ball, and if the player does not succeed in putting the object-ball in the

inclined way he is out, and three such "outs" constitute an inning. Nine innings constitute a game, and the player or side, if more than two players take part in the game, making the larger number of runs wins the game. If there be a tie, one or more innings may be played to decide the game.

The cue-ball and the object-ball are designed to be of different colors, and the cushion at the home corner, which may be constructed of stout wire, can be made of any other suitable material. The long side of the corner-cushion extends to the adjacent side cushion, and the other or shorter side terminates at one side of the entrance to the inclined way.

It will be seen that the game is exceedingly simple and inexpensive in construction, that it is adapted to afford a great amount of amusement to a number of persons, and that it may be constructed of various sizes to adapt it for both young and old persons.

What I claim is—

1. A game comprising a game-board having a field and provided with an inclined way surrounding the field, cushions arranged at the sides of the field, said cushions being spaced apart to provide entrances to the way, and balls, substantially as described.
2. A game comprising a game-board having a field and provided with an inclined way arranged outside the field, cushions located at the sides of the field and spaced apart, and a cushion arranged at the end entrance to the channel and adapted to return a cue-ball to the field, substantially as described.
3. A game comprising a game-board having a field and provided with an inclined way extending around the field, cushions arranged at the sides of the field and spaced apart to provide entrances to the way, an object-ball de-

signed to be arranged adjacent to the entrance of the way, a cue-ball designed to be arranged in the field, and a cushion arranged at the end entrance to the inclined way and adapted to return the cue-ball to the field, substantially as described.

4. A game comprising a game-board having a rectangular field and provided with an inclined way extending around the field, the straight cushions located at the sides of the field and spaced apart at the corners thereof, balls, and a curved cushion arranged at the end entrance to the inclined way and adapted to return a cue-ball to the field, substantially as described.

5. A game comprising a game-board having a field and provided with an inclined way arranged outside of the field and consisting of a groove or channel, side cushions arranged at the sides of the field and spaced apart to form entrances to the way, and a cushion arranged at the end entrance to the way and adapted to return a cue-ball to the field, substantially as described.

6. A game comprising a game-board having a marginal flange and provided with an inclined way consisting of a groove or channel extending around the board, the side cushions spaced apart and consisting of wires and suitable supports, and the approximately U-shaped corner-cushion extending from one of the side cushions to one side of the groove or channel, substantially as described.

In testimony that I claim the foregoing as my own I have hereto affixed my signature in the presence of two witnesses.

GEORGE LEWIS HOTCHKISS.
